[57] CLAIM

The ornamental design for a cross training exerciser, as shown and described.

DESCRIPTION

FIG. 1 is a perspective view of the cross training exerciser showing our new design;
FIG. 2 is a top view thereof;
FIG. 3 is a bottom view thereof;
FIG. 4 is a front elevational view thereof;
FIG. 5 is a rear elevational view thereof; and,
FIG. 6 is a side elevational view thereof the opposite side being a mirror image thereof except for the pedals being in an alternate position.
